UNITED STATES PATENT OFFICE.

HERMANN ZENKER, OF STEGLITZ, NEAR BERLIN, GERMANY.

WEAVING DEVICE.

Application filed September 2, 1921, Serial No. 498,036, and in Germany May 8, 1917.

(GRANTED UNDER THE PROVISIONS OF THE ACT OF MARCH 3, 1921, 41 STAT. L., 1313.)

This invention has reference to a weaving device wherein the warp is led in a zig-zag or tortuous manner over series of drums or cylinders mounted in the frame of the device. By this way a length of warp disproportionately great in comparison with the small dimensions of the device itself is obtained and a considerable length of material can be woven. The warp itself is formed from an endless thread moved by a mechanically driven drum or roller. The tension upon the warp may be secured and may be varied or adjusted by the displacement of one of the rows of drums with respect to the other. The shed or lease is formed by double oscillatory levers of different lengths having hook-shaped arms with fork-shaped bearings and being actuated by a tensioning or drawing device. In the said fork-shaped bearings of the double-armed levers, reeds, one in front of the other, are suspended.

The said reeds are composed of any number of thin plates of different lengths, fitted side by side and arranged in such a manner, that slots of different length are formed, a long narrow or wide slit being followed by a shorter narrow or wide slit. The sequence or order of the plates can be varied with the requirements. When rising the reeds always take up only the alternate or second thread. The long plates of the reeds render impossible any springing over of the threads.

The shuttle may be actuated by hand or by means of a throwing device. I prefer to employ a throwing-device actuated by a lever that may be moved to the left and to the right and besides in a forward direction for the purposes hereunto specified.

Two preferred forms of construction of my weaving device are shown by way of example on the accompanying drawing in which Fig. 1 is a longitudinal section through the first modification showing the arrangement of the warp and the operating mechanism for the double-levers carrying the reeds. Fig. 2 is a side-view of a double-lever adapted to carry the reeds. Fig. 3 is a partial front view of the same. Fig. 4 shows detail-views of the plates forming the reeds. The arrangements shown in Figs. 2-4 may also be employed with the second modification of the object of the invention. Fig. 5 is a longitudinal section through the second modification of the device, Fig. 6 il-

lustrates a vertical section along the line A—B of Fig. 5, Fig. 7 shows the adjusting mechanism, and Fig. 8 is the top view of the device. In all figures the same reference letters indicate the same parts.

In the drawings *a* is a desk-shaped casing, in the upper side of which, at the upper and lower extremities, slots *c* and *d* are provided, in which the warp-carrying drums rotate freely. In the position where the shed is to be formed, there is also a slot through which project the reeds *g*, *h*, which are fitted one in front of the other. On the inner side-walls of the frame are pivoted on the pin *i* the two double-levers having long arms *k*, *l*, and short arms *k'*, *l'*, this rendering possible, on the one hand, the positioning of the reeds one in front of the other, and, on the other hand, the rear end connection, formed between the short arms of each pair of the levers. The connection between the two levers forming a pair is advantageously effected by means of rods *r*, *s*. In the modification shown in Figs. 1-4 *m* are stationary carriers for the upper row of drums, which comprises several drums *o* arranged behind each other, and *n* are the corresponding carriers for the lower row of drums *p*. Said rails *n* are vertically displaceable by means of screws *q*. The warp is formed from a continuous thread and is led by a zig-zag path from the drum *f* alternately over the drums *o* and *p* in turn, finally over the drum *e* and the desk-top of the frame back to the starting carrying drum *f*, and then continued along the path hereinbefore described, till the warp is completed. The warp is brought up in the following manner. The thread coming from a bobbin once being conducted over all the drums, its starting end is connected to the thread coming from the bobbin, so that an endless winding results. Now by turning the carrying drum *f* this endless winding runs over all the rollers like a driving band and takes along with it the thread running from the bobbin, so that new windings forming the warp are made in such a number as corresponding to the latitude of the weft to be made and to the thickness of the thread employed. The drum *f* may be turned by hand or mechanically. The warp being completed the final end of the thread is connected to the last but one winding of the thread. The connection of the starting and final end of

the thread to the first and last but one winding of the warp may be done by splitting.

For the purpose of the lease- or shed-formation the reeds g , h are employed suspended by bearing pins x in the fork-shaped extremities of the double-armed levers l , l' . The short arms l^1 , l^1 (see Fig. 2) of said levers are attached by means of rods r , s with the tension-cords t , u (Fig. 1), which pass over guiding rollers v , v^1 , v^2 , and may be connected with an oscillatory device w .

The reeds g , h are made from long thin plates y and short thin plates y^1 , y^2 resp., which are united by screwbolts z^2 in such a manner that the reed shows long and short slits. When rising the reeds alternately, always the alternate or second thread is taken up, the long plates rendering impossible any disturbing of the warp.

With the second modification (Figs. 5-8) the casing a is provided in two parts that can be telescoped one into the other in order to be adjusted in height in the manner described below, so that by reason of the altered length of the warp resulting from such an adjustment woven pieces of varied and great length can be produced. While with the modification described the shuttle is moved by hand, with this second modification the shuttle is actuated by means of a lever that may be thrown to the left and to the right and in a forward direction. By means of this lever, adapted for movements in various directions, the weft can at the same time be pressed home against the work.

The means by which the case is adjusted to vary the space between the spindles of the warp carrying rollers comprise the outer portion of the casing 1 and the inner portion of the casing 2, the lower row of rollers 4 resting in the outer portion of the casing 1 and the upper row of rollers 3 resting in the inner portion of the casing 2. At the end walls of the portions of the casing a leverage mechanism 5 is provided, operating on the principle of the Nürnberg shears, which leverage mechanism can be actuated in a suitable manner, for example, by means of a crank 6, and fixed in position, with a predetermined space between the two rows of rollers, in accordance with the required length of the woven piece.

The lever 20 provided for actuating the shuttle 22 is situated within the space between the two front portions of the casing, and it is geared by means of a segmental rack 7 to a rack 8 which is continued in both directions on the frame 9, in such a manner, that, on the lever being moved to the left, the frame 9 is pressed to the right, and on the lever being moved to the right, the frame is pressed to the left. Hinged to a spring arm 10, of which one is provided at the left and at the right of the inner portion of the casing is a beater 12 standing rigidly when

it is acted upon in one direction and yielding when it is acted upon in the other direction. If the frame 9 is moved outward, its finger 11 engages the beater 12 and bends the spring arm 10 outward until the beater slides off the finger 11. Then arm 10 returns and its beater hits the shuttle, driving it out of its rest 23 along the shuttle race 13 attached to the weft pressing reed 21 through the thread into the opposite shuttle rest 24. When the frame 9 is returned by swinging the lever 20 in the opposite direction, the finger 11 tilts over the beater, when the frame 9 has passed in the direction of the arrow, which returns by the gravity of its lower arm in its upright position (see the additional figure to Fig. 6) so that the respective arm 10 is ready for new engagement which the respective finger 11 at the to-and-fro movement of the frame 9. By the movements of the lever to the right and to the left the warp threads are separated at the same time by the pressure arms 14 and 15, which in turn by means of studs 25, 26, actuate the reed support levers pivotally carried upon the spindle 16 and returning into its normal position by means of the weight of the reeds or springs not shown. The upper part 20' of the lever 20 can be turned backward and forward around the pivot 17. An eye 18 at the end of the pivoted part 20' of the lever 20 is connected with the weft pressing reed 21 by means of a rod 19 so that the weft pressing reed 21 is pressed home against the work after each shuttle stroke. The shuttle race 13 is attached to the weft pressing reed in order to simplify and ensure the correct action of the shuttle.

This second modification is operated to make a fabric in the following manner: The warp being completed in the manner described with relation to the first mentioned modification and the shuttle being brought into the position shown in Fig. 6 the lever 20 is moved to the left. Its stud 26 then lowers the rod 27 connecting the ends of the levers l' , l shown in the plan in Fig. 8 and raises the corresponding reed supported by the rods l^2 thereby forming the shed or lease. At the same time by means of the segmental rack 7 the lever 20 has moved the frame 9 to the right, which frame, the shed or lease being formed, bends and releases the beater so that it hits the shuttle and drives it through the thread into the opposite shuttle rest 24. The lever 20 is then returned into its normal position (Fig. 6) and its upper inset-part 18 turned backwards, so that the weft pressing reed 21 is pressed home against the work. The part 18 of the lever 20 is then returned to its normal position and the lever 20 is now moved to the right, thereby turning the levers l' , l by pressing down the rod 28 connecting the ends of said levers by means of the stud 25,

raising the corresponding reed supported by the rods k^2 and forming again the shed or lease. At the same time the frame 9 has been moved to the left so that the shuttle is hit by the left hand beater and is driven through the thread into the shuttle rest 23. The lever 20 is then turned again into its normal position and the inset part 18 turned backwards in order to press the weft pressing reed 21 home against the work. By continuously repeating the movements described of the lever 20 the fabric proceeds until the warp, moved forwards by turning the drum f , is exhausted.

15 I claim:

1. In a weaving device of the kind as described, the combination of warp-carrying drums, an upper system of rollers and a lower system of rollers over which a continuous warp thread is conducted in zig-zag fashion, means for varying the distances of the rollers of one of said systems from the rollers of the other of said systems in a vertical direction, shed-forming reeds, reed actuating arms, and pivotal connecting means between said reeds and said arms.

2. In a weaving device of the kind as described, the combination of warp-carrying drums, an upper system of rollers and a lower system of rollers over which a continuous warp thread is conducted in zig-zag fashion, means for varying the distances of the rollers of one of said systems from the

rollers of the other of said systems in a vertical direction, shed-forming reeds comprising dents separated by alternate long and short bars forming alternate long and short slots between said dents, said dents and separating bars being clamped on stringing members, reed actuating arms, and pivotal connecting means between said reeds and said arms.

3. In a weaving device of the kind as described, shed forming reeds, weft pressing reeds, and shuttle throwing means, a lever movable as a whole in one plane for actuating said shed forming reeds and said shuttle throwing means, said lever having a portion movable in a plane at right angle to the first plane for actuating said weft pressing reeds.

4. In a weaving device of the kind as described, shed forming reeds, weft pressing reeds and shuttle throwing means, a lever having an upper part and a lower part hinged together, means connected to the lower part of said lever whereby said lever being oscillated in full in one plane, said shed forming reeds and said shuttle throwing means are actuated, and means connected to the upper part of said lever whereby the upper part of said lever being oscillated in another plane, said weft pressing reeds are actuated.

In testimony whereof I affix my signature.
HERMANN ZENKER.
